Des. 215,851
Patented Nov. 4, 1969

215,851

HOUSING FOR A PHOTOMULTIPLIER OR SIMILAR DEVICE

Oskar Heininger, Framingham Center, Mass., assignor
to Sylvania Electric Products Inc., a corporation of
Delaware

Filed Oct. 15, 1968, Ser. No. 14,102

Term of patent 14 years

Int. Cl. D16—05

U.S. Cl. D26—14

FIG-2

FIG-4

FIG-3

FIGURE 1 is a perspective view of a housing for a photomultiplier or similar article showing my new design;

FIGURE 2 is a side elevation thereof;

FIGURE 3 is a front elevation thereof viewed on line 3-3 of FIGURE 2; and

FIGURE 4 is a top view thereof.

The conventional foot rest portions as well as the electrical cable bushing shown on the otherwise plain left side, depicted in broken lines are for illustrative purposes only.

I claim:

The design for a housing for a photomultiplier or similar device, as shown and described.
